Patented Nov. 11, 1913.

UNITED STATES PATENT OFFICE.

FREDERIC GALPIN, OF NEAR WILLIAMSFIELD, ILLINOIS.

SAW-SETTING MACHINE.

1,078,139.

Specification of Letters Patent.

Patented Nov. 11, 1913.

Application filed March 17, 1913. Serial No. 754,826.

To all whom it may concern:

Be it known that I, FREDERIC GALPIN, a citizen of the United States, residing near Williamsfield, in the county of Knox and 5 State of Illinois, have invented a new and useful Saw-Setting Machine, of which the following is a specification.

My invention relates to devices for setting the teeth of saws, and the primary object is 10 to provide novel means for successfully and with great facility accomplishing that end. And while the invention relates primarily to use of the peculiarly shaped co-acting wheels (presently described) as a means for 15 setting saw-teeth, it will be manifest that by turning either shaft (as 12) to actuate its wheel (as 19) said wheel will impart movement in the contrary direction to the other wheel (as 26) and thereby to its shaft, 20 and inasmuch as the couples thereof are flexible relatively to each other, also as later herein described, a flexible gear is provided.

It is an object to provide means the relative positions of some of the elements of 25 which may be readily altered to effect setting of saw-teeth widely different in construction (or constructive details) and size, as regards length, breadth, and thickness.

Another object is to provide co-acting 30 tooth-setting wheels having peculiar and novel structural characteristics.

Also it is an object to so construct each tooth of each wheel that when certain elements are dispensed with and the manner of 35 operation changed, whereby the saw is guided and moved between said wheels, it will be fed forwardly by said teeth.

It is to be understood from that which precedes, and as well from the description 40 soon to follow, that the broad idea of my invention contemplates not only means which move longitudinally of and on a held or stationary saw, but comprehends also certain changes in said means whereby the 45 saw may be moved through a portion of said means while the latter is not moving as a body, or traveling, but is rotating as in the other manner of operation. Concisely stated, the device has two modes of opera- 50 tion, either the saw being moved through the

tooth-setting wheels, or the latter moved over the saw-teeth.

Minor objects will be in part obvious and in part specifically pointed out.

In the accompanying drawings, which 55 illustrate a preferred embodiment of means for carrying my invention into effect, Figure 1 is a side (or end) elevation; Fig. 2, a similar view, but partly in section and some of the elements not shown, while some are in 60 changed relative positions from that shown in Fig. 1; Fig. 3, a rear elevation; and Fig. 4, an enlarged fragmental detail.

Referring to the drawings by numerals and uniformly employing the same one 65 thereof to designate the same part in each of the views, 2 indicates a base on which are secured a pair of standards 3, 4, and a pair of table-supporting legs 5, 5, on which is supported a table 6. The standards are pro- 70 vided each with an upper bearing, and in these are mounted the gudgeons 7, 8 of a swinging frame 9 provided with a guideway 10. 11 is a crosshead sliding in said way and apertured for the passage of a 75 shaft 12 on which is keyed a pinion 13 which meshes with the teeth of a rack 14 seated on an offset projection 15 on said frame 9.

16 is a spacing collar.

17 is a crank-arm on the pinion 13, and 18 80 the handle thereof.

Axially fixed on the forward end of the shaft 12 is an oval gear wheel 19, the top of each tooth of which is longitudinally arcuate, as shown best in Fig. 2—a contour 85 with which I have achieved the best results. Each tooth top is provided with a longitudinally arranged groove 37, for a purpose presently described.

Mounted in bearings in the lower portions 90 of the standards 3 and 4 are the gudgeons 21, 22 of a swinging frame 20 provided with a guideway 24 in which a crosshead 23 reciprocates. This crosshead also is transversely apertured for the reception of a shaft 25 for 95 which it is a bearing, and said shaft is either integral with or fixed to an oval gear-wheel 26 in mesh and preferably identical in construction with the wheel 19 and which, therefore, requires herein no further descrip- 100

tion. For the purposes of this specification the wheels 19 and 26 may be herein termed tooth-setting wheels.

Mounted in brackets 27 on the standard 3 is a shaft 28 to which is secured a worm or screw 29 the threads of which engage the teeth of upper and lower rack-arms or swinging segments, 30, 31, respectively, both of which are fixed to and on the gudgeons 8 and 22, respectively.

32 is a milled or knurled knob on the projecting end of the worm-shaft 28 and by rotations or part rotations of which the arms 30, 31 and thereby the upper and lower pairs of gudgeons may be moved to swing the upper and lower frames and simultaneously tilt or incline the saw-setting wheels at such angles or relationship to each other as may be predetermined, all of which is dependent upon the nature and characteristics of the saw to be operated upon.

33 designates a saw-clamp or yoke supported above the table 6 on the terminals of a pair of wing-screws 34, 35 by which it may be raised bodily or by adjustments of either of which it may be tilted or inclined as desired.

36 designates a clamping-screw for locking the saw within the clamp.

30 The operation: The saw having been secured in the clamp 33 said clamp may by means of either or both screws 34, 35 be raised, lowered, or tilted as desired, to bring the saw-teeth into proper relationship with the setting-wheels. These, it will be assumed, have been properly adjusted (as earlier herein described) by means of the worm 29. It will be noted that the longitudinally considered top of each tooth of 40 each of said wheels is arcuate and that the corresponding spaces between the pairs of teeth are likewise in contour, whereby when the wheels are tilted on their longitudinal axes that tooth which is resting in a space between two teeth in the companion wheel will rock therein, and that inasmuch as the teeth taper from a considerable width at their butts to a relatively narrow point at their tips, it is an easy matter to bring a tooth and its corresponding space into such 45 relationship that they will conform in size to saw teeth differing vastly in their widths. The proper adjustments having been determined and made, the operator will actuate 50 the crank-arm 17 and thereby the pinion 13 and shaft 12 to rotate the wheel 19 and thereby the wheel 26. As the teeth of these alternately engage spaces in the other, alternate saw-teeth will be forced upwardly or 55 downwardly, as the case may be, to properly set them, for the setting wheels will advance in a path longitudinally over and in contact with said saw-teeth and with ref-

erence to the rack 14 by reason of the pinion 13 meshing with the latter and moving 65 thereon, whereby the crossheads will move and operate in an evident manner.

Should it be desired to move the saw through the teeth of the setting wheels while they are rotating but otherwise stationary, the rack 14 is laid aside, whereupon rotations of the pinion 13 will impart like movement to the wheel 19 and thereby to the wheel 26. The saw-teeth tips or extremities will engage the shoulders providing the 75 grooves 37 and be fed along thereby and by the frictional contact of the tops of the setting-teeth.

While I am aware that saw-setting teeth have heretofore been devised, none to my 80 knowledge has been provided with an oval tooth-setting wheel or wheels such as I have shown and described, and it may be here stated that I consider the main feature or 85 gist of my invention, or that part thereof which relates to the saw-setting means *per se*, as residing therein.

Having thus described the nature of the invention and having illustrated and described preferred structural means for carrying it into effect, I claim as new and desire to secure by Letters Patent the following, to-wit:—

1. In a saw-setting machine, a toothed oval wheel tapering substantially to a point, 95 each tooth thereof provided with a longitudinal channel in its top, and means co-operating therewith whereby saw-teeth may be set.

2. In a saw-setting machine, a pair of 100 toothed oval wheels in mesh, means for rotating them, and means for advancing both while they are so rotating.

3. In a saw-setting machine, a pair of toothed oval wheels in mesh, a worm, and 105 means interposed between said wheels and worm whereby said wheels may be simultaneously tilted on their longitudinal axes.

4. A device of the character described comprising a pair of toothed oval wheels in 110 mesh, a saw-clamp, and means for raising, lowering, or tilting said clamp with reference to said wheels.

5. In a device of the character described, a pair of toothed oval wheels adapted each 115 to tilt longitudinally and one of them to impart rotary movement to the other, and means for imparting such movements thereto.

6. In a saw-setting machine, a pair of 120 toothed oval wheels in mesh, and means for rotating them, each tooth of at least one of said wheels being provided with a longitudinally arranged groove.

7. In a saw-setting machine, a pair of 125 toothed oval wheels in mesh, means for ro-

tating them, means for simultaneously tilting them longitudinally, swinging frames provided each with a way, and crossheads adapted each to travel in one of said ways whereby said wheels are caused to travel likewise.

In testimony whereof I hereunto affix my

signature at Galesburg, Knox county, Ill., this 7th day of March, 1913.

FREDERIC GALPIN.
